BOAT

James Wesley Ambrose, Portland, Oreg., assignor to
Earl O. Williams, Arcata, Calif.

Filed May 9, 1960, Ser. No. 60,487

Term of patent 14 years

(Cl. D71—1)

Fig. 1.

Fig. 2.

Fig. 5.

Fig. 1 is a side elevational view of a boat showing my new design;

Fig. 2 is a top plan view thereof;

Figs. 3 and 4 are front and rear elevational views, respectively, of the boat; and

Fig. 5 is a bottom plan view thereof.

The dominant features of my design reside in the portion shown in full lines.

I claim:

The ornamental design for a boat, as shown and described.
